Arthur B. Jenkins,
ATTORNEY

UNITED STATES PATENT OFFICE

GEORGE A. LONG, OF HARTFORD, CONNECTICUT, ASSIGNOR TO THE LONG SECURITY LOCK COMPANY, OF HARTFORD, CONNECTICUT, A CORPORATION OF CONNECTICUT

LOCK

Application filed November 18, 1927, Serial No. 234,257. Renewed July 3, 1929.

- My invention relates to that class of key operated locks that are more commonly employed for securing the doors or other closures to compartments of various kinds, my 5 improved lock being particularly applicable for use in connection with the doors of safe deposit boxes and similar compartments found in banks and other places, and an object of my invention, among others, is the 10 production of a lock in which the mechanism may be readily changed to prevent its operation by the key formerly fitting the lock and to require the use of a key differently bitted or notched to effect the operation.
- 15 One form of a lock embodying my invention and in the construction and use of which the objects herein set out, as well as others, may be attained, is illustrated in the accompanying drawings, in which—
- 20 Figure 1 is a face view of my improved lock, showing the bolt in its locking position. Figure 2 is a side view of the same.
- Figure 3 is a view in section on a plane denoted by the dotted line 3—3 of Figure 5.
- 25 Figure 4 is a similar view on a plane denoted by the dotted line 4—4 of Figure 5.
- Figure 5 is a view in section on a plane denoted by the dotted line 5—5 of Figure 3.
- Figure 6 is a view similar to Figure 5, but 30 showing the mechanism in its normally unlocked position.
- Figure 7 is a view similar to Figure 6, but showing the mechanism in a slightly different position and with the key center or barrel placed to permit a change in the combination of the leaf tumblers.
- Figure 8 is a detail view in section on a plane denoted by the dotted line 8—8 of Figure 7.
- 40 Figure 9 is a view of a key for operating my improved lock.
- In connection with safe-deposit boxes or similar compartments in banks or other places it has been found desirable to have 45 means for easily and quickly changing the "combination" whereby the use of a key differently bitted or notched from that formerly employed will be required to operate the lock mechanism, and my invention illustrated 50 and described herein effectually provides such a lock that comprises a case 6 formed in any suitable manner and provided with a cover plate 7 to close the chamber in the case and the mechanism therein.
- A barrel or key center 8 having a key opening 9 is rotatably mounted in the case and projects through the plate 7 on the front face of the case, as shown in Figs. 3 and 8 of the drawings. An escutcheon 10 on the plate 7 surrounds the projecting part of the key center 8, this escutcheon having notches 11 to receive opposite edges of a key to permit its insertion and removal in the normal operation of the lock, such escutcheon also having releasing notches 12 and 13 to permit removal of the key for a purpose to be hereinafter described. The barrel or key center 8 comprises a guiding section 14 to receive and guide a key into an actuator section 15 that is offset from the front end or guiding section, and as shown in Figs. 3 and 8 of the drawings.
- This actuator section has a key slot 16 shaped in a common manner to receive a key and it also contains holes for the members 17 of a set of pin tumblers which coact with the members 18 of another set of pin tumblers the latter being located in a pin tumbler block 19 secured within the casing and having a circular recess 20 to permit rotating movement of the key center, the wall of this recess also acting as a retainer and guide for the set 17 of pin tumblers. When the proper key 21 has been inserted in the slot 16, and as shown in Fig. 6 of the drawings, the dividing line 22 between all of the tumblers in the sets 17 and 18 will register with the plane of the wall 20 so that the center may be turned in a manner that will be readily understood by those skilled in the art.
- The key 21 has a set of pin tumbler notches 22 on one edge to properly locate the sets of pin tumblers and permit rotation of the key center, and said key has a set of bits 23 on its opposite edge to properly position a set 24 of leaf tumblers pivotally mounted in the case, said bits properly positioning the leaf tumblers to cause notches 25 in the ends of the tumblers to register to receive fingers 26 from a set of guards 27 slidably mounted on

a locking bolt hereinafter mentioned, the guards having retaining notches 28 each to receive one edge of a retainer 29.

In an unlocking operation (see Figure 5) the bits 23 properly position the leaf tumblers 24 after release of the key center and its rotation as above described with each notch 25 opposite a finger 26, and at this time a lug 30 projecting from the actuator 15 will enter 10 a recess in the edge of the bolt 31 to move the latter in its sliding movement in the case. This movement is permitted by reason of the fact that as the lug 30 enters the notch in the bolt the notches 25 and fingers 26 will register 15 properly to permit retracting movement of the bolt. During the forward or locking movement of the bolt, the retainer 29 will enter the notches 28 before the fingers 26 have been moved out of the notches 25. This engagement of the retainer 29 and notches 28 will preserve the location of the guards 27, relatively.

When it is desired to change the combination of the lock a change in position of one 25 or more of the tumblers 24 is made and this also simultaneously changes the position of a guard or guards 27 engaged with said tumbler or tumblers. This change in position of the guards causes the retainer 29 to 30 be received in a different notch or notches in the guard or guards so changed. The positioning of the tumblers for the purpose just described may be effected by the key that is to be employed after the combination is 35 changed. This manner of changing a combination has been effected prior to my invention and it will, therefore, be readily understood, and for this reason and the fact that much of the mechanism thus far described 40 is of well known construction a further and more detailed description is omitted herein.

My invention contemplates means whereby this change in combination by altering the position of one or more of the tumblers 24 45 may be readily effected and without any liability of a movement of any of the parts to alter the relative arrangements thereof while such change is being made. Should any of the parts be unintentionally moved relatively 50 to other parts, the arrangement would be so disturbed as to require the lock to be taken down and the parts then properly arranged.

In effecting my purpose I provide a holder for the key center, this holder being in the 55 form of a stud 32 projecting from a holder slide 33 slidably mounted in the case and having a button 34 located outside of the case for the purpose of operating the slide. The stud 32 is adapted to engage within one 60 of the holes for the pin tumblers 17, and the slide 33 is urged into this locking position as by means of a spring 35.

The slide supporting the holder 32 may be operated differently than as herein specifically shown and I contemplate other means for

accomplishing this purpose as within the spirit and intent of my invention as defined by the claims herein.

The stud 32 operates as a stop to limit the rotating movement of the key center in its 70 unlocking movement, and as shown in Figure 6 of the drawings. It will thus be seen that I not only make use of this as a holder for the key center, but I also employ it to stop the rotation of the key center in its unlock- 75 ing movement.

To change the combination of the lock the button 34 is used to push the slide 33 backwardly when, by the use of the old key, the center 8 is moved into the resetting position shown in Figure 7 and against the stop 36. At this time, the button 34 having been released, the spring 35 will force the stud 32 into a hole occupied by one of the tumblers 18, said tumbler being moved backward 85 against the force of its spring. The key center is now locked in this resetting position.

During the rotation of the key center from its normal or unlocked position, shoulders 37 on the key pass behind a lip around the center opening in the escutcheon, and a holding bit 39 passes behind the tumblers 24. This prevents the removal of the key, in prior structures, until the key center is rotated backwardly to its normal or unlocked position. In adapting my invention, I form releasing notches 38 in the tumblers 24 so located that when the key center is rotated to the position shown in Figure 7, the bit 39 may pass outwardly through said notches to permit removal of the old key, the shoulders 37 simultaneously passing through the releasing notches 12 and 13.

While the key center is locked in this resetting position, as shown in Fig. 7, a new key, differently bitted from that of the key removed, is inserted in the key center, its prong 39 entering through the notches 38 and the shoulders 37 through the notches 12 and 13, the button 34 is pushed back, releasing the key center, and the new key is used to turn the key center backwardly. The differently formed or what may be termed changed bits 23 on the new or substituted key now act to reposition one or more of the tumblers 24 under the action of the tumbler springs, and this also automatically repositions the guards 27 by reason of the fact that the fingers 26 are at this time in the notches 25. The key being turned to place the key center in its unlocking position one or more of the tumblers will be thus automatically positioned in a new combination, and the stud 32 will be automatically returned to position to stop opening movement of the key center in further operation of the lock. The notches 28 are so arranged that they will be properly engaged by the retainer 29 in this new position of the guards 27.

It will thus be seen that I have provided 126

means whereby the key center is positively locked during the time that the old key is being removed and a new key is being replaced and all the parts are thus preserved in their relative positions, and after the change has been effected, after the holder 32 for the key center has been removed, the parts will, in a locking movement of the key, be automatically returned to their normal operative condition, but with one or more tumblers and guards in the new position or positions effected by the change in the combination.

In accordance with the provisions of the patent statutes I have described the principles of operations of my invention, together with the device which I now consider to represent the best embodiment thereof; but I desire to have it understood that the device shown is only illustrative and that the invention may be carried out by other means and applied to uses other than those above set out.

I claim—

1. A lock mechanism including a key receiving member, members adapted to be positioned by said key to control operations of the lock mechanism, and means other than said members for automatically holding said receiving member against movement while a change of keys is made preparatory to altering the position of at least some of said controlling members.

2. A lock mechanism including a key receiving member, members adapted to be positioned by said key to control operations of the lock mechanism, and means other than said members for automatically engaging and holding said key receiving member against movement while a change of keys is made preparatory to altering the position of at least some of said controlling members.

3. A lock mechanism including a key receiving member, members adapted to be positioned by said key to control operations of the lock mechanism, a stop to limit movement of said key receiving member, and means on said key receiving member to receive said stop and hold said key receiving member against movement while a change of keys is made preparatory to altering the position of at least some of said controlling members.

4. A lock mechanism including a key receiving member, members adapted to be positioned by said key to control operations of the lock mechanism, a manually operable stop to limit movement of said key receiving member, and means for automatically engaging said stop with said key receiving member to hold the latter against movement while a change of keys is made preparatory to altering the position of at least some of said controlling members.

5. A lock mechanism including a key receiving member having holes for pin tumblers, members adapted to be positioned by

said key to control operations of the lock mechanism, and means to engage in one of said holes to hold said key receiving member against movement while a change of keys is made preparatory to altering the position of at least some of said controlling members.

6. A lock mechanism including a key receiving member having holes for pin tumblers, pin tumblers located in said holes to control movement of said key receiving member, members adapted to be positioned by said key to control operations of the lock mechanism, and means to enter a pin tumbler hole against a pin tumbler therein to hold said key receiving member against movement while a change of keys is made preparatory to altering the position of at least some of said controlling members.

7. A lock mechanism including a key receiving member, members adapted to be positioned by a key to control operations of the lock mechanism, and means selectively acting in either of two capacities with respect to said key receiving member whereby the latter will be limited in its movement in one or both of two directions.

8. A lock mechanism including a key receiving member, locking members adapted to be positioned by said key to control operation of the lock mechanism, means acting upon the key receiving member to permit further rotation of said key receiving member after unlocking the said mechanism to locate the working edge of a key in space free of said locking members and to prevent additional movement after further rotation occurs, and means to permit removal of said key and the insertion of another key while so positioned.

9. A lock mechanism including a key receiving member, locking members adapted to be positioned by said key to control operation of the lock mechanism, means to permit movement of said key receiving member to position the working edge of a key in space clear from said locking members, means to lock said key receiving member against movement when in said position, and means to permit removal of said key and the insertion of another key while in said position.

10. A lock mechanism including a movably mounted key receiving controller member, locking members operable by a key in said controller member for releasing said controller member, a locking bolt engageable with said controller member for operation thereby, locking members operable by a key in said controller member to release said bolt, and means for holding the controller member against movement, while the bolt is in its unlocked position, to permit of a change of keys.

11. A lock mechanism including a movably mounted key receiving controller member, locking members operable by a key in said controller member for releasing said control-

ler member, a locking bolt operatively connected with said controller member for operation thereby, locking members operable by a key in said controller member and during rotation of said controller member to release said bolt, and means for holding the controller member against movement, while the bolt is in its unlocked position, to permit of a change of keys.

12. A lock mechanism including a movably mounted key receiving controller member, locking members operable by a key in said controller member for releasing said controller member, a locking bolt operatively connected with said controller member for operation thereby, key operated members for locking said bolt against initial movement and operable by a key in said controller member and during rotation of said controller member to release said bolt, and means for holding the controller member against movement, while the bolt is in its unlocked position, to permit of a change of keys.

13. A lock mechanism including a movably mounted key receiving controller member, key operated members for locking said controller member against movement, a locking bolt, key operated members for locking said bolt against movement, a key having one portion formed to release said controller locking members and another portion to release said bolt locking members, and means for holding the controller member against movement, while the bolt is in its unlocked position, to permit of a change of keys.

14. A lock mechanism including a key receiving member, a key having oppositely positioned working edges insertable in said member, a locking bolt, key actuated members operable by one edge of said key to release said key receiving member, a key actuated member operable by the opposite edge of said key for releasing said bolt and means for changing the setting of the last mentioned key actuated member.

15. A lock mechanism including a key receiving member, locking members adapted to be positioned by a key in said receiving member to control operations of the lock mechanism, means acting upon the key receiving member to permit disengagement of a key from said locking members with the latter in their bolt releasing positions, means for retaining said locking members in fixed relative positions during such disengagement of the key therefrom, and including a part of the key receiving member, and means to permit removal of said key from said receiving member when so disengaged.

16. A lock mechanism including a key receiving member, locking members adapted to be positioned by a key in said receiving member to control operations of the lock mechanism, means acting upon the key receiving member to permit disengagement of a key

from said locking members with the latter in their bolt releasing positions, means for retaining said locking members in fixed relative positions during such disengagement of the key therefrom, and including a part of the key receiving member, means to permit removal of said key from said receiving member when so disengaged, and a member to engage said retaining means before disengagement of the latter from said locking members and to prevent relative disarrangement of said retaining means.

17. A lock mechanism including a receiving member, members adapted to be positioned by a key in said member to control operations of the lock mechanism, means for limiting movement of said receiving member in normal operations of the lock mechanism, and means for permitting positioning said key receiving member in a different position preparatory to a change of tumbler combination thereafter holding said key receiving member in such position during a change of keys.

18. A lock mechanism including a key receiving member, members adapted to be positioned by a key in said member to control operations of the lock mechanism, means for limiting the movement of said receiving member in normal operations of the lock mechanism, and means for permitting excess movement of said key receiving member to a position for removal of the key preparatory to a change of tumbler combination thereafter to hold said key receiving member in such position during such removal.

19. A lock mechanism including a key receiving member, members adapted to be positioned by a key in said member to control operations of the lock mechanism, means for limiting the movement of said receiving member in normal operations of the lock mechanism, means for permitting excess movement of said key receiving member to a position for removal of the key preparatory to a change of tumbler combination, and means for locking said receiving member in said position.

20. A lock mechanism including a key receiving member, a set of members adapted to be positioned by a key in said member to control operations of the lock mechanism, a number of guards engageable each with a member of said set and releasable therefrom, means for retaining said guards in their normal positions when released from said retaining means but releasable therefrom to permit movement of said members for effecting a change in key combination, and means for permitting excess movement of said key receiving member to a position for removal of the key preparatory to a change of tumbler combination and for thereafter holding the key receiving member after such excess movement.

21. A lock mechanism including a key re-

ceiving member, a set of members adapted to be positioned by a key in said member to control operations of the lock mechanism, a number of guards engageable each with a member of said set and releasable therefrom, means for retaining said guards in their relative positions when released from said retaining means, but releasable therefrom to permit movement of said members for effecting a change in key combination, means for permitting excess movement of said key receiving member to a position for removal of the key preparatory to a change of tumbler combination, and means for retaining said member against movement during such change of key combination.

22. A lock mechanism including a key receiving member, members adapted to be positioned by a key in said member to control operations of the lock mechanism, a stop for limiting movement of said key receiving member in normal locking and unlocking operations of the lock, and means including said stop for positioning and holding said key receiving member in an abnormal position for a change in tumbler combination.

23. A lock mechanism including a key receiving member, members adapted to be positioned by a key in said member to control operations of the lock mechanism, a stop for limiting movement of said key receiving member in normal locking and unlocking operations of the lock, said stop being movably mounted, means for removing said stop from the path of said key receiving member to permit the latter to be positioned for a change in tumbler combination and means for moving said stop into a position to hold the key receiving member in its abnormal position.

24. A lock mechanism including a casing, a pin tumbler block mounted therein, a key receiving member rotatable with respect to said block, means carried by the block for preventing rotation of the key receiving member until a proper key has been inserted in said member, and additional means carried by said block selectively active in either of two capacities with respect to said key receiving member whereby the latter will be limited in its movement in one or both of two directions.

25. A lock mechanism including a casing, a pin tumbler block mounted therein, a key receiving member rotatable with respect to said block, means carried by the block for preventing rotation of the key receiving member until a proper key has been inserted in said member, and means carried by the block in spaced relation with respect to the aforementioned means for normally limiting movement of the key receiving member under the influence of a key and for selectively permitting abnormal movement of the key receiving member.

26. A lock mechanism including a casing, a pin tumbler block mounted therein, a key receiving member rotatable with respect to said block, means carried by the block for preventing rotation of the key receiving member until a proper key has been inserted in said member, spring pressed means carried by the block for normally limiting the movement of the key receiving member, and means for controlling said spring pressed means for permitting the latter to hold the key receiving means in an abnormal position while a change of keys is effected.
